UNITED STATES PATENT OFFICE.

HENRY A. IDDINGS, OF WARREN, OHIO.

DIE FOR FORMING LINKS.

SPECIFICATION forming part of Letters Patent No. 286,013, dated October 2, 1883.

Application filed October 31, 1882. (No model.)

To all whom it may concern:

Be it known that I, HENRY A. IDDINGS, of Warren, in the county of Trumbull and State of Ohio, have invented a new and useful Improvement in Dies for Forming and Welding Links, of which the following is a full, clear, and exact description.

My invention relates to the form and construction of the upper and lower dies used for forming links, the object being to facilitate the work and to produce links having greater strength than those heretofore made by the usual operation.

The invention consists in lower dies of peculiar construction and arrangement, and the combination thereof with an anvil that is formed to receive the dies.

It also consists in means for raising or loosening the dies; and it consists, further, in upper dies of a form and construction especially adapted for use with the lower dies hereinbefore mentioned, all as hereinafter described and claimed.

Reference is to be had to the accompanying drawings, forming part of this specification, in which similar letters of reference indicate corresponding parts in all the figures.

Figures 1, 2, 3, and 4 show the anvil and lower dies. Figs. 5, 6, 7, and 8 show the upper dies.

Referring to Figs. 1 and 2, A and A' are the lower dies, set in the recessed anvil E, which is shown as cut away on one side sufficiently to show the flange a on the side of the die A'. In Fig. 1 the anvil-block has the sides of its recess formed as the segment of a circle, while in Fig. 2 one side is made partly vertical at 1, and the upper portion is shaped in the segment of a circle.

The dies A A' are formed with flanges a on their sides, as shown most clearly in Figs. 3 and 4, which take into corresponding grooves in the anvil-block, so that as the dies are raised in the block they are forced open.

The mandrel or former b, for the center of the links, is made of different shapes, as illustrated in Figs. 3 and 4, according to the shape of the metal that is used for forming the links. In the sides of the dies are openings c c, which allow the admission of tongs for grasping and handling the links as they are put in or taken out.

d d, Figs. 1 and 2, are levers fitted transversely in the anvil-block beneath the dies, for use in raising the dies from the block; but the dies may be raised by any levers or power appliances, as may be found most desirable in the several uses to which the dies may be put, and each die may be raised by its own lever; or one lever may be employed to raise both dies at the same time.

The upper dies are shown in Figs. 5 to 8. Fig. 5 is a side view, an edge view, and a bottom view of the die, the lower portion of which, below the shoulder or collar g, is made of the requisite thickness for passing between the sides of the lower dies and over and around the outside of the link-blank as it lies on the mandrel or link-center. The lower end is cut out or beveled at 2, so as to pass more readily outside of the link and press the blank inward toward the link-center or mandrel. This form is more especially intended for link-blanks having their cut ends bent together, although it may be used upon crooked or U-shaped link-blanks, and in either case aids in the making of a perfect link. This die is arranged for square metal. For round or D-shaped metal, the die is made as shown in Fig. 6, in which case it is formed with a semicircular groove in the faces of the surfaces, that take upon the outside of the link-blank. Fig. 7 shows an upper die of the same form, but made in two pieces, so that the edges of one side may pass or slide up above those of the other portion. This construction is in order that a long lap may be given to the ends of the link-blanks when it is desired to thicken the ends of the links, in order to obtain greater strength at those points. Fig. 8 shows the die made in two parts, as in Fig. 7, and held in the head of the hammer D.

h is a wedge, which, when withdrawn from above the die, allows one portion to rise and assume the position shown in Fig. 7, the wedge being fitted for operation by means of a lever, i.

I², Fig. 8, is a side view, showing the form of the dies when they are made in two portions, and when more strength is required they will be formed with flanges k k, as shown in the same figure.

The upper dies may be made of any length desired; but for ordinary work they are preferably made to extend to the bottom of the

- lower dies. When they do not extend to the bottom of the lower dies, the latter may be filled up at the sides to correspond with the length of the upper dies.
5. By the use of dies constructed and arranged as described, the work of forming and welding links can be readily carried out, and the welding can be done more perfectly than by dies such as usually used.
10. In operation the link-blank, after being heated and placed in position for welding, will be straightened, and any irregularities that may exist will be removed, and by the same blows of the hammer which bend over the ends of a U or press in the sides of an oval-shaped link a lap and a stove weld is formed. The construction shown allows for an enlarged amount of metal at the weld, and the link is quickly forced to shape without change of the dies.
15. By means of the openings in the dies the finished chain can be more readily held, and by the use of the split or divided upper dies an extra lap can be made at the weld, thereby making the link much stronger. Further, by using an upper die with the segment at the bottom thrown higher up than would be natural in a regular uniformly-shaped link, the links can be made thicker at their ends, and
20. then, by heating the other end of the link thus formed and using lower dies with a shorter link-center or mandrel, the other end of the link can be thickened, thereby placing more

metal at the ends of the links, where there is 35 the greatest wear.

Having thus described my invention, what I claim as new, and desire to secure by Letters Patent, is—

1. The lower dies, A A', formed with link-mandrels, substantially as shown and described. 40
2. The combination of the lower dies, A A', formed with the flanges *a*, with the recessed anvil *E*, having grooves, substantially as shown and described. 45
3. The combination, with the lower dies, A A', provided with the flanges *a*, and the recessed anvil *E*, having grooves, of means, substantially as shown and described, for raising the dies, as specified. 50
4. The lower dies, formed with the openings *c c*, to admit tongs for holding a finished link, as specified.
5. The upper die, B, centrally slotted, so as to pass around the link, and having the ends of its arms internally beveled at 2, substantially as described, and for the purpose set forth. 55
6. The combination of the upper dies, B, formed with their lower ends beveled at 2, with the lower dies, A A', and anvil-block *E*, substantially as described. 60

HENRY ALFRED IDDINGS.
